W. H. EAVES

HOLLOW BRICK AND WALL CONSTRUCTED THEREFROM

Filed April 10, 1923

UNITED STATES PATENT OFFICE.

WALLACE H. EAVES, OF ATLANTA, GEORGIA, ASSIGNOR TO EAVES HOLLOW BRICK COMPANY, OF ATLANTA, GEORGIA, A CORPORATION OF GEORGIA.

HOLLOW BRICK AND WALL CONSTRUCTED THEREFROM.

Application filed April 10, 1923. Serial No. 631,080.

To all whom it may concern:

Be it known that I, WALLACE H. EAVES, a citizen of the United States, residing in the city of Atlanta, county of Fulton, State of Georgia, have invented certain new and useful Improvements in Hollow Brick and Wall Constructed Therefrom, of which the following is a specification, reference being had to the accompanying drawings, forming a part thereof.

My invention relates to hollow brick for building purposes and to the construction of walls from such brick and has for its object to produce brick adapted to be laid in the same manner and with the same manual labor as ordinary brick and will, at the same time be of such dimensions that with this same manual labor and in the same time a wall of twice the height may be built as could be constructed of ordinary solid brick. A further object of the invention is to provide hollow brick which will be adapted for use as stretcher and for bonding and for corners so that a complete and perfect wall may be built of the brick of my invention without the use of ordinary brick for bonding or corners. A further object of the invention is to provide hollow brick which may be made at a cost less than that of ordinary brick and may be burned at less cost.

Hollow brick or tile as heretofore used have been of relatively large dimensions not adapted to be made with an ordinary brick machine, relatively weak and of such weight as to require both hands of the brick layer in placing them in position necessitating dropping his trowel after spreading the mortar, lifting the hollow tile into position and again picking up the trowel.

By the use of my invention the difficulty and delay so resulting is obviated.

Having the objects above indicated and other objects hereinafter described in view my invention consists in the brick and in the wall construction formed therefrom as hereinafter described and claimed.

Referring to the drawings:

Figure 1 is a side view of the stretcher brick of my invention.

Figure 2 is a cross sectional view of the same,

Figure 3 is a central longitudinal sectional view of the bonding brick of my invention and

Figure 4 is an end view of the same.

Figure 5 is a perspective view of a finished wall corner formed of the brick of my invention.

Figure 6 is a perspective view of a partly constructed wall.

Figure 7 is a diagrammatic vertical sectional view of a wall of varying thickness constructed of the bricks of my invention.

In the drawing AA indicate the longitudinal or stretcher form of the hollow brick and BB indicate the header or bonding form.

The longitudinal or stretcher bricks AA are formed of a length corresponding to that of an ordinary brick, that is about eight inches or a little less, and a width corresponding to that of the ordinary brick, that is a little less than four inches. Its height is approximately four inches. Through the brick from end to end extends the opening A¹. The side walls A², A³, and the top and bottom walls A⁴ and A⁵ are of substantial thickness, not less at any point than three-quarters of an inch and at the junction of the side walls with the top and bottom walls they are made thicker as indicated at —a— so that the longitudinal opening A¹ will be of rectangular shape in cross section but with rounded corners. The material used in the side and top and bottom walls is in the aggregate considerably less than that required to form the two bricks which fill the same space. The hollow brick is thus of considerably less weight than two bricks and is not sufficiently greater than that of an ordinary brick to present any difficulties to handling it with one hand as in laying ordinary brick. The width of the hollow brick being substantially the same as that of the ordinary brick it can be grasped by the one hand in the same manner. Thus the hollow brick may be placed in position by the brick-layer with one hand leaving the other hand free to use the trowel to apply and spread the mortar. The hollow brick may therefore be laid with the same rapidity that ordinary brick are laid and as the hollow brick is twice the height of ordinary brick the wall will rise at twice the rate with the same amount of manual labor.

The ends of the hollow stretcher brick AA are cut off at right angles with the longitudinal lines so that in laying a wall each

stretcher brick abuts at its ends squarely against the next brick.

The header or bonding brick BB are of the length of an ordinary, approximately 5 eight inches, four inches in height and of substantially the same width as an ordinary brick, the same or approximately the same as the width of the stretcher bricks, slightly less than four inches. Vertically through 10 the header or bonding brick extend openings B¹ and B² of approximately the same size as the opening A¹ in the stretcher brick. Between the two openings B¹ and B² is formed parallel with them, a narrow opening B³ rec- 15 tangular in cross section with relatively sharp corners. The walls of the openings B¹ and B² are thickened at the corners as shown at —b— so that the openings while of rectangular shape have rounded corners. 20 When it is desired to make use of a half brick a sharp blow on the side of the bonding brick in line with the openings B³ will cause the brick to break in line with this opening in the sharp angles at the ends of the opening, 25 lying between the thickened corners of the openings B¹ and B² tending to make the line of the opening B³ so much less strong than the line of the openings B¹ and B² that the break caused by the blow of the trowel, or 30 other instrument, will follow the line of this opening B³ and the brick will be readily divided into two substantially equal halves.

By reason of the openings B¹, B² and B³ the material necessary for the bonding brick 35 will be materially less than that of two ordinary bricks and as the width is substantially the same as that of an ordinary brick it may be readily grasped in one hand for placing it in position.

40 By reason of the thickness of the walls of the bricks they will sustain a crushing strain amply sufficient for use and not greatly less than the crushing strain which will be sustained by ordinary brick.

45 The upper and lower faces of the stretcher brick may be corrugated or roughened as shown at C to give increased surface for the mortar to adhere to.

In building a wall the courses will be 50 mainly of the stretcher brick as indicated in Figures 6 and 7. At the outside of each corner a brick of the bonding form will be used, as shown in Figure 5, the stretcher bricks on one side abutting against the side, 55 of this bonding brick and on the other side, abutting against its end. Where, as is usually the case, the wall is to be not less than eight inches in thickness, the brick of the inner row of bricks at the corner abuts at 60 its end against the side of a stretcher brick and, for half its length, abuts on one side against the side of the bonding brick which forms the corner, as clearly shown in Figure 5. The inner row of bricks will thus 65 break joints with the outer row.

At suitable intervals a row of bonding bricks BB will be laid on the rows of stretcher bricks as shown in Figures 6 and 7 thus effecting a firm bonding of the wall.

Where the wall is to be twelve inches in thickness the bonding may be effected by laying a course consisting of bonding bricks at right angles to the stretcher bricks with a row of stretcher bricks in front of (or in rear of) the row of bonding bricks.

The bricks, both the stretcher bricks and the bonding bricks, are adapted to be used in the same way and with the same expenditure of manual labor as are ordinary bricks. The form of both is such that they may readily be made by the ordinary brick machine of the type in which the clay is forced out through a mold and cut off at suitable intervals. By reason of the hollow construction these bricks may be burned more quickly and with less expense for fuel than can ordinary brick.

There is thus, by reason of the construction a saving in expense of production and, with the same amount of manual labor, a 50 wall of twice the height can be built in substantially the same time. There will also be a substantial saving in the amount of mortar used.

The width of the bricks will depend on 55 the thickness of the layer of mortar to be used and should be four inches less the thickness of the mortar.

The hollow bricks of my invention being 60 relatively small in size are much stronger 100 than the larger sized hollow blocks or tile and may be shipped with less damage from breakage and at less expense.

In building a wall of eight or more inches in thickness the stretcher bricks present an 105 outer clay wall formed by the wall A² of the inner bricks, and a central wall midway between the outer and inner walls consisting of the wall A³ of the outer bricks, the wall A² of the inner bricks, and the intermediate layer of mortar. The openings A¹ extending through the bricks from end to end form air spaces and prevent passage 110 of moisture. The wall constructed of these bricks will therefore be impervious to moisture forming a completely dry wall.

As the bonding brick are placed in position upon courses of stretcher brick the walls between the openings B¹ and B² will be in the same vertical plane with the center 120 wall formed by the inner wall A² of the outer stretcher brick and the outer wall A² of the inner stretcher bricks. The end walls of the openings B¹ and B² will be in the same vertical plane with the outer wall A² 125 of the outer stretcher brick and with the inner wall A² of the inner brick so that the complete wall will present a continuous outer vertical wall, a continuous inner vertical wall and a continuous central vertical 130

wall midway between the inner and outer walls and separated from them by air spaces. The continuous vertical walls thus formed are adapted to sustain great crushing strain and the portions between these vertical walls are relieved from this strain.

Having thus described my invention, what I claim is:

1. A wall formed of parallel rows of hollow stretcher bricks each having an opening therein extending from end to end and hollow bonding bricks each having two vertical openings therein and each opening approximately of the same cross sectional area as that of the opening in a stretcher brick, and having a relatively thick web between the openings, the bonding bricks being so arranged relatively to the parallel rows of stretcher bricks that the end walls of the bonding bricks are in vertical alignment with the front and rear outside walls of the stretcher bricks and the transverse web of the bonding brick is in vertical alignment with the adjacent walls of the stretcher
25 bricks.

2. A wall formed of parallel rows of hollow stretcher bricks each having an opening therein extending from end to end, and hollow bonding bricks each having two vertical openings therein each approximately of the same cross sectional area as that of the opening in a stretcher brick and having a relatively thick transverse web between the openings with a vertical central opening therein, the bonding bricks being so arranged relatively to the parallel rows of stretcher brick that the end walls of the bonding brick are in vertical alignment with the front and rear outside walls of the stretcher bricks and the transverse web of the bonding brick is in parallel alignment with the adjacent walls of the stretcher brick and the vertical opening in said web is in vertical alignment with the space between said adjacent walls of the stretcher
35
40
45 brick.

In testimony whereof I hereunto affix my signature.

WALLACE H. EAVES.
